GASOLINE CAMP STOVE.

Application filed May 3, 1926. Serial No. 103,389.

This invention relates to improvements in gasoline camp stoves of the type now quite extensively employed by automobile tourists and campers.

5 It is the object of this invention to produce a stove of a substantial and neat design which can be cheaply constructed and which at the same time will have many advantages over stoves of this type that are constructed 10 in the usual manner.

It is a further object of this invention to produce a stove that shall have means by which gasoline may be readily conducted to the priming cup, without necessitating 15 the removal of the gasoline tank.

It is a still further object of this invention to produce a stove in which the gasoline tank shall be permanently connected to the burners and the manifold and in which the 20 tank and burners can be removed as one complete assembly.

The above and other objects that may become apparent as the description proceeds are obtained by means of a construction and 25 arrangement of parts which will now be described in detail, reference for this purpose being had to the accompanying drawing in which the preferred embodiment has been illustrated and in which:

30 Fig. 1 is a top plan view with a part of the cover and grate being broken away so as to show the position of the tank and burners when the stove is in inoperative position;

Figure 2 is a view similar to that shown in 35 Figure 1, but shows the burners and tank in operative position;

Figure 3 is a section taken on line 3—3, Figure 2;

Figure 4 is a section taken on line 4—4, 40 Figure 2;

Figure 5 is a vertical section taken on line 5—5, Figure 4;

Figure 6 is a section taken on line 6—6, Figure 1;

45 Figure 7 is a section taken on line 7—7, Figure 2; and

Figure 8 is a section taken on line 8—8, Figure 4.

The improved stove to which this invention relates comprises an enclosing casing having end members 1, 2, side members 3, 4 and bottom member 5. A sheet metal cover 6 provided with openings 7 and 8 is hinged to the rolled top 9 of the side 4. 55 Grates 10 of a suitable construction are se-

cured in the openings 8 in the manner shown in Figure 2. The casing is also provided with a hinged cover 11. The stove consists of two burners 12 and 13, which are connected to opposite ends of a tubular manifold 14, in the manner indicated in Figure 5. From Figure 5 it will be noted that the burner 13 is made in two parts, the lower of which has been indicated by numeral 15. The part 15 has a central tubular projection 60 16 that extends through a hole in the upper surface of the manifold and has its edge crimped outwardly so as to rivet it to the manifold. A valve member has an enlarged head 17 whose conical sides 18 engage the 65 sides of the opening in the tubular member 16. This valve has a stem 19 that projects through an opening in the lower side of the manifold and into a short tube 20 in whose side a helical slot 21 has been cut. A pin 22 70 is connected to the valve stem 19 and projects perpendicularly therefrom. This pin passes through the slot 21 in the manner shown in Figure 4. It is evident that by rotating the pin about the axis of the valve stem, it will 75 be caused to move upwardly or downwardly, as the case may be thereby raising or lowering the valve so as to control the admission of gas to the interior of the burner 13. Burner 12 is constructed in exactly the same 80 manner as burner 13, but is not provided with a valve or with a valve controlled mechanism. The ends of the manifold are closed by means of cup-shaped plugs 23.

Referring now more particularly to Figure 90 4, it will be noticed that iron straps 24 have one end bent into a U-shaped formation in the manner shown and indicated by reference numeral 25. The sides of this U-shaped portion are provided with shoulders 26 that 95 serve as supports for the longitudinal ribs 27 of the manifold, which are connected to the shoulders by being spotwelded thereto. The extreme end of the strap 24 has been indicated by numeral 28 and extends upwardly and outwardly at an angle which corresponds to the inclined portion indicated by numeral 29. The burners 12 and 13 are secured to the inclined parts 28 and 29 by means of clamping members 30. From 100 the inclined portion 29, the straps extend upwardly and outwardly to the point 31 from which they extend downwardly in the manner indicated by numeral 32. Below 105 this portion they are curved in the arc of 110

a circle which curved portion has been indicated by numeral 33, and the extreme end is bent reversely in the manner indicated by numeral 34. An arcuate strap 35 has its straight end 36 secured to the end 34 by means of a rivet 37 and has its other end connected to the strap 24, between sections 32 and 33, by means of a bolt 38. From the above it will be seen that the tank is rigidly attached to the manifold and burners by means of the two straps 24. The manifold 14 is provided with an opening 39 at a point substantially half way between the two burners. A bearing member 40 is electro-welded to the upturned flange 41 of the manifold and has the lower portion 42 flared outwardly in the manner shown in Figure 7. A curved tubular member 43 is provided near its end with a shoulder 44 which engages a similar shoulder on the bearing member 40, and has its extreme end expanded as indicated at 45 so as to fit against the inner surface of the conical portion 42. The pipe 43 is rotatably connected to the manifold by the means just described and shown in Figure 7.

The tubular member or pipe 43 is curved through an arc of ninety degrees and is there provided with a downwardly extending opening 46 which terminates a short distance above the upper surface of the manifold.

Located directly above the burner 12 is a generator 47 whose end projects into the horizontal end portion of the tubular member 43 when the parts are located in the manner shown in Figure 2, where the upper portion of the horizontal part of tubular member 43 has been broken away to show the position of the end of the generator 47. This generator is connected to the tank 48 by means of a pipe 49 and a valve member 50, in the manner shown in Figures 1 and 2. The valve 50 has a hand wheel 51 by means of which it can be moved from open to closed position and vice versa.

Extending laterally from the horizontal portion of the tubular member 43 is a channel 52, to the end of which a spout 53 is secured. One end of this spout is entirely enclosed in the manner indicated by numeral 54. By rotating the tubular member 43 in the bearing by which it is connected to the manifold, it can be moved from the position shown in Figure 2 to the position shown in Figure 1 and vice versa.

In the operation of the stove, the gasoline is contained in the tank 48 and is subjected to a moderate pressure by means of air which is forced into the tank by the pump 55. When the valve 50 is open, gasoline from the tank will flow through the pipe 49 and through the generator 47. Before the stove will operate properly, this gasoline must be converted into vapor by means of

heat and it is therefore necessary to heat the generator 47 to such a temperature that it will vaporize the gasoline as it flows through it.

For the purpose of heating the manifold, it is necessary to fill the priming cup 56 with gasoline, which is then ignited. In starting the stove therefore, the pipe 43 is rotated in a counterclockwise direction from the position shown in Figure 2, to the position shown in Figure 1, in which position the gasoline that issues from the end of the generator 47 will strike the closed end of the part 54 and will flow through the trough 53 into the priming cup 56. When the priming cup has been filled with gasoline, the valve 50 is closed; the tubular member 43 is moved back into the position shown in Figure 2 and the gasoline in the priming cup is then ignited. When the gasoline in the priming cup has been nearly consumed, the valve 50 is again open and the gasoline which now flows through the generator will issue in the form of vapor which will pass into the tubular member 43 where it will become mixed with air sucked in through the opening 46. This mixture of air and vapor will then pass through the manifold into the burner 12 and emerge through the perforations in this burner, when it will ignite and the heat from the burning gas will continue to keep the generator of sufficient temperature to vaporize the gasoline.

If one burner only is desired, the valve 17 may be retained in closed position; but if two burners are needed, the valve 17 is opened and part of the gas will then flow into burner 13 and can be ignited. For the purpose of opening and closing the valve 17, I have provided a slide 57, which is attached to the straight portion of the strap 24 that corresponds to the burner 13. This slide member has a downwardly projecting side 58, whose end is provided with an opening 59 to which one end of the connector 60 is connected. The other end of this connector is bent at right angles in the manner indicated by reference numeral 61 and this end projects through an opening in the pin 22. The side 58 is also provided with another opening 62, which receives the end 63 (Fig. 8) of the wire 64 whose outer end 65 extends over the top of the gasoline tank 48. A clip 66 has one end electro-welded to the side 68 and has the end portion 67 offset and projecting upwardly above the end 63 so as to hold it from outward movement. A clip 68 is attached to the strap 24 and encloses the wire 64 in the manner shown in Figures 2 and 4. It will now be apparent that when the wire 65 is pulled to the left in Figure 4, it will rotate the pin 22 in the helical slot 21 and cause it to move upwardly, thereby opening the valve 17. And when it is moved towards the right, it

will close the valve. By this means, therefore, the escape of gas through the burner 13 can be regulated and entirely prevented if desired.

5 When the stove is to be used the parts are moved to the position shown in Figures 2, 3 and 4, in which position the tank 48 is located on the outside of the wall 3, and the burners 12 and 13 are located directly beneath the grates 10. The end 2 is provided with a notch 69 which receives the part of the valve indicated by numeral 70.

10 After the stove has been used and when it is desired to transport it, the parts are moved to the position shown in Figure 1, where the tank burners and valves are all enclosed within the casing. When the parts are assembled as shown in Figure 1, the cover 11 can be closed and the entire 15 stove will then be in a very compact form, which is convenient for handling and in which the operative parts are protected against injury.

Having now described the invention what 20 is claimed as new is:

1. A gasoline vapor stove comprising in combination, a tubular manifold closed at both ends, a burner connected to the manifold, a tubular mixing chamber pivotally attached to the manifold so as to be in communication with the interior thereof, and movable with respect thereto, a priming cup associated with said burner and manifold, a trough secured to one side of the mixing chamber and a generator tube extending over the priming cup said tube being adapted to communicate with the trough or the mixing chamber.

2. A gasoline vapor stove having a manifold, a mixing chamber pivotally secured thereto, a burner secured to the manifold, a depression in the upper surface of the burner, a fuel tank, a generator tube located above the depression in the burner and connected with the tank, the free end of said generator opening into the mixing chamber, a trough carried by the mixing chamber and adapted to cooperate with the generator tube to direct fuel into the depression in the burner when the mixing chamber is in one position.

3. A gasoline vapor stove comprising, in combination, a tubular manifold, a burner secured thereto and having its interior in communication therewith, a mixing chamber

pivotaly attached to the manifold, a generator tube having one end connected with a fuel tank and the other adapted to cooperate with the mixing chamber when the latter is in one position and a trough attached to the mixing chamber, said trough being so located that it can be moved into position to receive fuel from the generator tube and to conduct the fuel to a priming cup.

4. A gasoline vapor stove comprising, in combination, a tubular manifold closed at both ends, a burner connected to the manifold near each end, a tubular mixing chamber pivotally attached to the manifold intermediate the burners, said mixing chamber having a trough secured to one side, a generator tube extending over one of said burners and adapted to communicate with the interior of the mixing chamber or the trough.

5. A gasoline vapor stove comprising, in combination, a tubular manifold having its ends closed, a burner secured to the manifold near each end thereof and having their interior in communication with the interior of the manifold, means comprising a valve mechanism for controlling the passageway to one of said burners, a tubular mixing chamber pivotally attached to the manifold, a generator tube extending over one of said burners, a priming trough secured to one side of the mixing chamber and adapted to be moved into line with the generator tube.

6. In a gasoline vapor stove, in combination, a tubular manifold, a burner connected to and in communication with the interior of the manifold, said burner having its upper surface depressed so as to form a priming cup, a gasoline tank secured to the manifold, a generator tube having one end in communication with the interior of the tank, said tube extending over the priming cup, a tubular mixing chamber pivotally attached to the manifold so as to be movable into and out of operative relation with the generator tube and a priming trough attached to one side of said mixing chamber and adapted to be moved into operative relation with the generator.

In testimony whereof we affix our signatures.
